LIQUID APPLYING DEVICE

John S. Stull, Chicago, Ill., assignor to Western
Electric Company, Incorporated, New York,
N. Y., a corporation of New York

Application December 2, 1937, Serial No. 177,755

2 Claims. (CL 91—38)

This invention relates to a liquid applying device, and more particularly to a device for applying liquid materials to articles.

An object of the invention is to provide a simple and efficient device for applying liquid material to articles.

In accordance with one embodiment of the invention there is provided a device for applying acetone to cellulose acetate coil covers to secure the covers to the coils. The device comprises a container for holding a supply of acetone, a felt wick having one end thereof partially submerged in the acetone and its opposite end exposed for contacting the coil covers therewith, and means for deflecting the exposed end of the wick to vary the amount of acetone therein.

Other features and advantages of the invention will become apparent from the following detailed description when read in conjunction with the accompanying drawing, in which

Fig. 1 is a plan view of an acetone applying device embodying the invention;

Fig. 2 is a vertical sectional view taken on line 2—2 of Fig. 1;

Fig. 3 is a fragmentary front view, partly in section on line 3—3 of Fig. 1, and

Fig. 4 is a fragmentary detail section on line 4—4 of Fig. 1.

Referring to the drawing, the device illustrated comprises a horizontal supporting plate 10 having a rearwardly extending portion 11, which is suitably formed for attaching or supporting the device on a work bence or table (not shown) so that the plate 10 will be positioned a suitable distance above the top of the work bench. Removably attached to the underside of the plate 10 is an open top receptacle or container 12 having a forwardly projecting channel-shaped lip 13 communicating with the interior of the receptacle.

The receptacle is attached to the plate 10 by means of a pair of thumb screws 15, 16 threaded into the side edges of the plate. The shank portions of the thumb screws fit into open top slots 16, 17 in the upper edges of the side walls 17, 18 of the receptacle. The side walls 17 extend above the rear wall and slidably engage opposite side edges of the supporting plate and are clamped thereto by the heads of the thumb screws when the latter are screwed into the plate. To remove the receptacle, it is necessary only to turn the thumb screws sufficiently to release their clamping pressure on the side walls of the receptacle.

In the illustrated embodiment of the invention, 55 the receptacle 12 is adapted to contain a bath 20

of liquid material, such as acetone. A felt wick 21 is provided for drawing the acetone from the receptacle. The wick is supported intermediate its ends in the channel-shaped lip 13 of the receptacle so that one end of the wick extends rearwardly into the interior of the receptacle while the opposite end of the wick projects forwardly from the front edge of the lip. The supporting plate 10 is provided or formed with a transverse wall or baffle 23 which projects downwardly into the receptacle and serves to hold the inner end of the wick partially submerged in the relatively small quantity of acetone contained in the bottom of the receptacle, as shown in Fig. 2. Rearward movement of the wick is limited by 18 a pair of lugs 24, 24, which project upwardly from the bottom of the receptacle.

The exposed forward end of the wick lies underneath a metal plate 25, which is pivoted or hinged at its rear edge between a pair of spaced 20 ears or lugs 26, 26 depending from opposite sides of the forward end of plate 10. The wick is preferably composed of a felt material that has sufficient stiffness, even when saturated, so that the exposed forward end thereof will normally tend 25 to assume a horizontal position in line with the supported intermediate portion of the wick. An adjusting screw 30 is provided in the forward end of supporting plate 10 above the hinged plate 25 so that by turning the screw in one direction 30 the hinged plate and the exposed forward end of the wick are deflected downwardly. Thus, the exposed or applicator end of the wick is vertically adjustable with respect to the level of the acetone in the receptacle, whereby the amount of acetone 35 that is drawn by capillary action into the exposed end of the wick or, in other words, the degree of saturation of the exposed end of the wick may be varied as required.

Means is provided for maintaining the acetone 40 at a constant level within the receptacle. This means comprises a cylindrical tank 32 adapted to hold a supply of the acetone. The tank is removably supported upon the plate 10, the latter having a tubular wall 33 projecting upwardly 46 therefrom for centering the tank with respect to a circular opening 34 in the plate. Threaded into the bottom of the tank is a discharge tube 35 having a discharge port 36 communicating with the interior of the tank. Within the tube a 50 spring pressed shut-off valve 38 is provided for automatically closing the discharge port 36 when the tank is lifted from the device, for example, for the purpose of refilling it or to place it in a storeroom when the device is not in use. The 55

valve has a depending rod 39 adapted to engage the bottom of the receptacle 12 and thereby effect the opening of the valve as the tank is lowered into position on the supporting plate 10.

5 The exterior end of the discharge tube 35 extends into the receptacle 12 to a point slightly above the bottom thereof, whereby only a relatively small amount of acetone is constantly maintained within the receptacle, which need be 10 sufficient only to partially submerge the inner end of the wick.

It is believed that the operation of the device will be obvious from the foregoing description. The flow of acetone or other liquid to the exposed 15 or applicator end of the wick is quickly adjustable by manually turning the adjusting screw 30. Upon turning this screw in one direction the exposed end of the wick is lowered and the flow of the liquid through the wick is thereby increased. When the adjusting screw is turned in 20 the opposite direction the exposed end of the wick rises by reason of its resiliency and the flow of liquid is thus decreased.

In Fig. 2, there is schematically shown in dotted 25 lines a portion of an electrical coil 43 having a cellulose acetate faced cover 42 partially wrapped around the winding. The cover is of sufficient length to provide overlapping end portions. As shown in the drawing, the inner surface of the 30 outer end portion of the cover is pressed lightly

against the exposed end of the felt wick 21 to receive a coating of acetone which causes the overlapping end portions of the cover to adhere firmly to each other when pressed together.

It is to be understood that the invention is not 5 limited to the particular construction and embodiments herein illustrated and described, except insofar as is defined by the appended claims.

What is claimed is:

1. A liquid applying device comprising a liquid 10 containing receptacle, a wick having one end partially submerged in the liquid and its opposite end extending exteriorly of the receptacle, a hinged plate for controlling the position of the exterior end of the wick, and an adjusting screw 15 for shifting the plate to change the position of said exterior end of the wick to thereby vary the flow of the liquid thereto.

2. A liquid applying device comprising a support, a liquid-containing receptacle suspended 20 from said support, a wick having one end partially submerged in the liquid and its opposite end projecting laterally from the receptacle, a plate pivotally suspended from said support and in contact with the upper surface of the laterally 25 projecting end of the wick, and means for angularly shifting said plate to deflect the projecting end of the wick and thereby vary the flow of liquid thereto.
